UNITED STATES PATENT OFFICE.

CHARLES DEUCK, OF WASCO, CALIFORNIA.

WRENCH.

1,156,764.

Specification of Letters Patent. Patented Oct. 12, 1915.

Application filed April 16, 1915. Serial No. 21,735.

To all whom it may concern:

Be it known that I, CHARLES DRUCK, a citizen of the United States, residing at Wasco, in the county of Kern and State of California, have invented new and useful 5 Improvements in Wrenches, of which the following is a specification.

This invention relates to wrenches, and the primary object of the same is to provide 10 a device of this class having a plurality of nut sockets or nut engaging openings of various sizes and contours as well as gripping jaws for engaging a pipe or nut associated with an extensible stock whereby 15 the wrench structure as a whole may be lengthened or shortened to adapt it for engagement with nuts or other devices in various positions that cannot be readily reached from the exterior of the mechanism 20 or apparatus with which they may be used by means of an ordinary wrench, the one portion of the stock being in the form of a stem telescopically fitted in a tubular member of the stock, and under certain conditions the stem has a locking association with 25 the tubular member to prevent rotation of the stem.

The invention consists in the construction and arrangement of the several parts which 30 will be more fully hereinafter described and claimed.

In the drawing: Figure 1 is a side elevation of a wrench embodying the features of the invention. Fig. 2 is a longitudinal 35 vertical section of the same showing the one part extended in relation to the other in dotted lines. Fig. 3 is a detail perspective view of the socket member of the wrench showing the stem thereof slightly modified 40 and illustrated as solid. Fig. 4 is a detail perspective view of the gripping jaws and pivot and spring accessories forming part of the jaw member of the wrench.

The numeral 5 designates a tubular stock 45 having one extremity for a considerable portion of its length formed with exterior screw-threads 6 and the terminal of the same extremity slotted, as at 7, to receive a pair of jaws whose jaw members 8 have their inner ends lapped and engaged by a pivot pin 9, a V-shaped spring 10 being interposed between the jaws and engaging the pivot pin to normally distend the jaws when the latter are free to move outwardly. Each of 55 the jaws 8 has a shank 11 with an outer convex surface 12 regularly continuing to the

rear terminal of the shank and the inner sides of the shanks as at 13, are practically longitudinally straight and therewith the legs 14 of the spring 10 have loose engagement. The inner opposing faces of the jaws are toothed, as at 15, to provide for a gripping action of the jaws relatively to a pipe or other device with which they may be engaged, and the inner opposing sides of the 60 jaws are longitudinally grooved, as at 15^a, to receive the legs 14 of the spring and thereby permit the jaws to be tightly closed, and the spring legs are also protected by this grooved construction and prevented from 65 being crushed or injured by the devices gripped by the jaws. The screw-threads 6 are provided for the adjustment of a clamping sleeve 16 mounted on the tubular stock 5 and correspondingly interiorly screw-threaded, as at 17. The sleeve is tubular and the inner surface of the front extremity thereof is beveled, as at 18, and the front end edge is rounded, as at 19, so that the front end of the sleeve will easily ride over 70 or engage the convex surfaces 12 of the shanks 11 of the jaws. The front end of the sleeve 16 is also formed with a plurality of slots 19^a of such width as to permit the 75 shanks of the jaws to move outwardly in the slots, the screw-threaded portions of the front extremity of the stock 5 projecting over the opposite sides of the jaws at points in diametrical relation to the slot 7 in the 80 said front extremity of the stock for receiving the jaw shanks. Between the slots 19^a the front end of the sleeve 16 is provided with bearing surfaces 19^b, which, when in engagement with the edges 12 of the shanks 11, hold the jaws 8 against movement in accordance with the adjustment of the sleeve. 85

It will be seen that by rotating the sleeve 16 the slots 19^a may be readily brought into registration with the shanks 11 of the jaws 8 to permit the said jaws to freely and automatically open through the action of the legs 14 of the spring 10, and then the jaws may be tightened against the pipe or other device with which they are placed in engagement by shifting the sleeve 16 forwardly over the screw-threads 6. The sleeve 16 is increased in thickness at its central portion or tapers toward opposite ends, and in the said central thickened portion thereof a plurality of nut sockets 95 20 are formed, said sockets having various dimensions or contours to accommodate en-

gagement thereby with square, hexagonal or other nuts. By providing the sleeve 16 with the nut sockets 20 the use and application of the improved wrench are increased, or 5 the wrench is given a greater scope as to its service in adapting the same for nuts of varying sizes and shapes. Extending transversely across the interior of the stock 5 adjacent to the jaws 8 is a locking pin 21, and 10 on the opposite end of the said stock a cap 22 is fitted and held by coöoperating screw-threads formed in the two parts. The cap 22 has a central opening 22^a surrounded by an 15 flange 23, and between the said flange and the adjacent end of the stock 5 a soft packing of oiled leather or other analogous material 24 is interposed and slightly projects inwardly beyond the wall of the bore of the stock 5 or has an opening 25 20 therein of less diameter than the said stock bore, and likewise the opening 22 in the cap is smaller in diameter than the stock bore, and by means of the annular flange 23 the packing 24 is positively held in place. 25 Within the stock 5 a stem 26 is telescopically mounted and may be tubular, as shown by Fig. 2, or solid as shown by Fig. 3; and on the rear end of the said stem a head 27 is secured and is formed from tubular material 30 or is a cylinder which is intersected at its side portion by the said stem 26. The head 27 has nut sockets 28 and 29 of different forms and dimensions in the opposite ends, and at diametrically opposite points in the 35 side are other sockets 30 and 31, which as shown are of square form or adapted for square nuts of different dimensions, the wall of the cylinder or head 27 being filed or cut-away, as at 32, to provide flat bearing 40 surfaces for a square nut and the remaining end walls 33, by reason of the convexity of the cylindrical head, serve as bearing means against opposite sides of the nut. In the head 27, at a point diametrically opposite 45 the attachment of the rear end of the stem 26 to the head, a nut socket 34 is formed which is shown as hexagonal in contour, but may be of any shape or dimensions. The head 27 is enlarged, as at 35, and formed 50 with a screw-threaded bore 36 to receive the rear screw-threaded extremity 37 of the stem 26; and as an additional securing precaution a set-screw 38 is inserted through a portion of the enlargement 35 and caused to 55 impinge against the screw-threaded extremity 37 of the stem 26 to reliably fasten the head 27 to the stem. The stem 26 is telescopically disposed in the stock 5 and has frictional engagement with the packing 24 60 to prevent the stem from having loose movement within the stock when the stock and stem are adjusted to extend the complete device when it is desired to reach inwardly into machinery or part of a vehicle or other apparatus to engage a nut for application or 65 removal thereof, or for any other purpose that may be found necessary where the wrench as a whole may be practically operated. The end of the stem 26 opposite that carrying the head 27 is formed with a cross or diametrical slot 39 to engage the pin 21 and thereby prevent the said stem from rotating within the stock during operations requiring a rotation of the complete wrench, as for instance when engaging the socket 34 70 in the head 27 with a nut or causing the jaws 8 to coöperate with a part that may be required to be tightened or loosened, and under such conditions it will be understood that the stem 26 will be fully inserted with- 75 in the stock 5. The tubular stock 5 is formed with a longitudinal groove 5^a on the inner side thereof to receive the projecting end of a pin 26^a secured in the stem 26 adjacent to the slot 39. The object of this 80 groove 5^a and projecting pin 26^a is to hold the stem 26 against rotation in the stock 5 when said stem is projected outwardly to lengthen the device as may be desired. The pin 26^a and groove 5^a operate mainly when 85 the stem 26 is disengaged from the pin 21, but when said stem engages the pin 21 the groove 5^a and pin 26^a conjointly act to hold the stem against rotation and resist break- 90 age of the pins when heavy stress is imposed on the stem in releasing tight nuts or in applying nuts of various forms. The wrench may be used with sidewise action in 95 engaging either of the sockets 28, 29, 30 or 31 of the head 27 with a nut or either of the 100 sockets 20 of the sleeve 16, and the jaws 8 may also be used when the stem is extended or pushed into the stock 5 with equal efficiency. 105 From the foregoing the operation of the improved wrench will be readily understood and in addition to the head serving as a nut socket means it will also be convenient as a gripping device for operating the nut and pipe engaging features at the opposite 110 extremity of the wrench, especially when the slot 39 of the stem is in engagement with the pin 21. When any one of the sockets in the head 27 is used or applied to a nut the 115 opposite extremity of the wrench will be gripped, the hands of the operator being preferably applied to the sleeve 16, but the exterior portions or edges of the jaws 8 and their shanks 11 are smooth and the hand of the operator can also be applied thereover without injury and with convenience in obtaining a strong grip on the wrench. 120

What is claimed is:

1. A wrench of the class specified comprising a tubular stock with movable nut engaging means and an interiorly located cross-pin at one end, and a stem telescopically fitted in and extensible in relation to said stock and having its end within the stock formed with a cross slot to engage said

- cross-pin to prevent rotation of the stem when the latter is projected to its predetermined maximum extent within the stock, the exterior end of the stem having a cylindrical head fixed thereon. 5
2. A wrench of the class specified comprising a tubular stock with nut engaging means at one end and a cap on the opposite end having an annular end flange around an opening therethrough of less dimensions than the bore of the stock, the flange of the cap being disposed a distance in rear of the adjacent end of the stock, an annular packing held between the annular flange of the cap and the end of the stock and projecting into the stock, and a stem extensibly mounted in the stock and movable through the said cap and packing and having a head on its end exterior of the stock, the packing frictionally engaging the stem and obviating loose movement of the latter in the stock. 10
3. A wrench of the class specified comprising a tubular stock with movable nut engaging means and an interiorly located cross-pin at one end and friction means at the opposite end, and a stem extensibly mounted in the stock and having engagement with said friction means and also provided with a slot at its end within the stock 25 to engage the said cross-pin to prevent rotating movement in the stock of the stem when the latter is fully projected within the stock, the friction means obviating too loose movement of the stem relatively to the stock 30 when the stem is extended outwardly from the stock and the slot in the stem disengages from the pin in the stock, the end of the stem exterior of the stock being provided with a head. 35
4. A wrench of the class specified comprising a stock with an exteriorly screw-threaded slotted extremity, a pair of gripping jaws mounted in said slotted extremity and having shanks with outer regular con-
- vex edges, a spring having legs engaging the inner edges of the said jaw shanks, and a sleeve of elongated form adjustably mounted on the said screw-threaded extremity of the stock and having slots in the front end thereof to permit the jaws to move outwardly, the intermediate portion of the sleeve being thickened. 45
5. A wrench of the class specified comprising a tubular stock having an inner groove and also provided with movable nut engaging means and an interiorly located cross-pin, and a stem telescopically fitted in and extensible in relation to said stock and having its end within the stock formed with a cross-slot to engage the said cross-pin and also provided with a pin having a projecting end to engage the groove in the stock, the exterior end of the stem having a cylindrical head fixed thereon. 50
6. A wrench of the class specified comprising a tubular stock with movable jaws at one end having grooves extending longitudinally of the inner opposing faces thereof, a spring engaging the jaws and having legs movably fitting in the said grooves, a cross-pin located interiorly of the stock adjacent to the jaws, the stock also provided with a longitudinal groove on the inner side thereof and a stem telescopically fitted in and extensible with relation to said stock 60 and having its end within the stock formed with a cross-slot to engage the said cross-pin and also provided with a projecting pin to engage the groove of the stock to prevent rotation of the stem in the stock, the exterior 65 end of the stem having a head fixed thereon. 70
- In testimony whereof I have hereunto set my hand in presence of two subscribing witnesses.
